UNITED STATES PATENT OFFICE.

OLIN J. GARLOCK, OF PALMYRA, NEW YORK.

ROD-PACKING.

No. 854,287.

Specification of Letters Patent.

Patented May 21, 1907.

Application filed February 20, 1907. Serial No. 358,452.

To all whom it may concern:

Be it known that I, OLIN J. GARLOCK, of Palmyra, in the county of Wayne and State of New York, have invented a new and useful Improvement in Rod-Packings, which improvement is fully set forth in the following specification and shown in the accompanying drawings.

My invention relates to machinery packing generally but more particularly to the kind and class known and understood as rod packing, and the invention has for its object the production of a fibrous slab of improved construction and makeup, and of packing rings formed from such slab.

It is known and understood in the matter of packing reciprocating and other similar rods, that the fibrous strands or threads comprising the packing rings will wear away more rapidly when the sides of the same are in contact with the rod and subjected to its abrasive action than if the ends of the strands meet the rod. In view of this fact, and other matters, I have produced a slab of packing material made up of layers or plies of fibrous material, the component strands or threads of which lay in various prearranged relative directions, the strands of adjacent layers forming angles varying from 30 degrees upward, so that rings cut from the slab will be such that the ends of substantially all the threads or strands will be directed against the surface of the rod.

Other objects and advantages of the invention will be brought out and made to appear in the following description, and the novel features particularly pointed out in the appended claims, reference being had to the accompanying drawings which, with the reference characters marked thereon, form a part of this specification.

Figures 1 and 2 represent portions of slabs constructed in accordance with my invention, parts of each being broken away. Fig. 3 is an edge view indicated by arrow in Fig. 1. Fig. 4 shows a similar slab with the threads of the various plies or layers slightly differently arranged. Figs. 5 and 6 show packing rings formed from the slabs shown in Figs. 1 and 4 respectively, parts of each being broken away.

The slab 1, shown in Figs. 1 and 3, has its plies or layers 2 to 8 inclusive, made of asbestos cloth the layers being relatively so placed and arranged that the threads or

strands 1' of adjacent layers cross each other at angles varying substantially from sixty to one hundred and twenty degrees, as clearly shown in Fig. 1. The layers or plies are so relatively placed that the threads of the upper one, 2, incline to the right, for example; those of the second layer, 3, being horizontal or longitudinal of the slab, while those of the third layer 4 incline to the left. From this it will be understood that a ring, 14, cut from the slab 1 will have all the threads of every layer turned substantially endwise toward the inner surface of the ring and thus directed against the surface of the inclosed rod on six sides, this being clearly seen by the portions of the layers 2, 3 and 4 uncovered by breaking away superincumbent parts. The strands of the layers below 4 are similarly arranged, those of the layers 5, 6 and 7 being respectively the same as the strands of the layers 2, 3 and 4, and those of the bottom layer 8 being as in the layer 2. It will also be seen that a ring cut from a slab constructed as shown in Fig. 2 would be practically the same as the ring 14, as to the relative arrangement of the layers and the directions taken by the component threads.

A slab constructed as shown in Fig. 4 has all the threads of the adjacent layers 10 to 13 forming angles of ninety degrees and a ring formed from this slab would have the ends of the threads directed against the rod on four sides, as clearly appears in Fig. 6. It will be understood, however, that the exact order of the layers, or the relative directions of the threads of the layers, is not essential to this invention, the main object in producing these improved packing rings being to arrange the component parts so that the ends of the threads or strands shall be directed toward and in contact with the surface of the rod.

The slabs, without regard to internal construction, are covered on both flat sides with thin layers of india-rubber, 9 and 9', the inclosed layers of asbestos cloth being joined by rubber cement, and the whole body put under pressure and vulcanized.

What I claim as my invention and desire to secure by Letters Patent is:

1. A slab of packing material for rods, formed of layers of cloth joined by an adhesive substance, the threads of the adjacent layers crossing each other at different angles whereby the ring cut from said slab

will have all the threads of each layer turned endwise toward the inner surface of the ring.

2. A slab of packing material for rods formed of layers of cloth joined by an adhesive substance, the threads of the adjacent layers crossing each other at different angles whereby the ring cut from said slab will have all the threads of each layer turned endwise toward the inner surface of the ring

to contact with the rod, and a covering for 10 the flat sides of said slab.

In witness whereof, I have hereunto set my hand this 16th day of February, 1907, in the presence of two subscribing witnesses.

OLIN J. GARLOCK.

Witnesses:

JOHN L. TRAVERS,
FRANK P. HEINEMAN.
